United States Patent Office

Des. 227,122
Patented June 5, 1973

227,122

FACSIMILE TRANSCEIVER APPARATUS OR SIMILAR ARTICLE

Robert A. Clowe, Penfield, N.Y., assignor to Xerox
Corporation, Stamford, Conn.

Filed May 8, 1972, Ser. No. 251,498

Term of patent 14 years

Int. Cl. D14—03

U.S. Cl. D26—14 R

FIG. 2

FIG. 3

FIG. 6

FIG. 1 is a left-hand front perspective view of a facsimile transceiver apparatus.

FIG. 2 is a top plan view thereof.

FIG. 3 is a front elevational view thereof.

FIG. 4 is a left-hand side elevational view thereof.

FIG. 5 is a right-hand side elevational view thereof.

FIG. 6 is a rear elevational view thereof.

I claim:

The ornamental design for a facsimile transceiver apparatus or similar article, as shown and described.
